By Alex. J. Wedderburn, Jr.

UNITED STATES PATENT OFFICE.

EDWARD J. CHRIST, OF PHILADELPHIA, PENNSYLVANIA.

AMUSEMENT DEVICE.

1,244,702.

Specification of Letters Patent. Patented Oct. 30, 1917.

Application filed September 16, 1912. Serial No. 720,579.

To all whom it may concern:

Be it known that I, EDWARD J. CHRIST, a citizen of the United States, residing at Philadelphia, in the county of Philadelphia and State of Pennsylvania, have invented 5 certain new and useful Improvements in Amusement Devices, of which the following is a specification.

This invention relates to improvements 10 in amusement devices and has for its object to provide a vertically traveling car adapted to automatically receive a load at its highest point of travel and be carried down by the weight of said load and dump said 15 load at its lowest point of travel and then automatically ascend for another load.

Another object of the invention is to provide a continuous automatically operated elevator.

With the above and other objects in view 20 I have invented the device illustrated in the accompanying drawings in which—

Figure 1 is an elevational view of my 25 device showing a car about to receive a load. Fig. 2 is a vertical central sectional view of a car,

Fig. 3 is a view similar to Fig. 1 showing the car on its downward trip,

Fig. 4 is a view partially in elevation and 30 partially in section of the lower part of a shaft showing a car in its lowermost and dumping position, and

Fig. 5 is a top plan view of the device.

Like reference characters indicate like 35 parts throughout the specification and in the several views in the drawings in which 1 indicates an elevator shaft consisting of four upright angle members 2 mounted upon a base 3 and having a top 4. On the 40 top 4 is a pair of opposing members 5 which form bearings for a pulley shaft 6 upon which is fixed the pulley 7 and projecting from the rear of the top 4 is an arm 8 which forms a bearing for a pulley 9. A cable 10 operating over said pulleys has a weight 11 secured to its outer end and a car 12 operating 45 in said shaft 1 secured to its inner end, said cable passing through an opening 13 in said top 4, the weight 11 being sufficiently 50 heavier than the car 12 to raise the car to the top of said shaft.

Mounted on the upper portion of said members 2 and outwardly thereof is an inclined trough or runway 14 for balls 15, 55 having a mouth 16 projecting into said shaft and pivotally mounted above said

mouth is a trip 17 having a stop 18 on its outer end and a stop 19 on its inner end and a trip arm 20 adapted to be engaged by the handle 21 of the car 12 and raised thereby 60 raising the member 19 and permitting the ball held by said member to roll onto the seat 22 in said car the weight of which added to the weight of the car overbalances the weight 11, thereby causing the 65 car to descend. When the member 20 is raised by the contact of the car handle the stop 18 is caused to descend between the ball 23 and the ball 24 next thereto thus preventing said last ball from entering the car 70 until its next trip. When the car starts down the weight of the member 20 causes it to drop raising the stop 18 and permitting the ball 24 to roll into position next the stop 19, when it will be in position to enter the car 75 when on its next trip up, when its handle 21 raises the members 20 and 19 thus permitting the escape of the ball held by said stop.

On the base 3 is a stop 25 so positioned as 80 to be engaged by the rear end of the car 12 whereby said car is caused to dump its load whereupon being relieved of the weight thereof it will immediately be caused to ascend by the overbalancing weight 11, 85 when the above described movements will be repeated and continuously repeated until all of the balls 15 in the runway 14 have been carried to the bottom of the shaft 1.

Fixedly mounted upon the ends of the 90 rotating pulley shaft 6 are paddles or pin wheels 26 which may be variegated in color to give an attractive appearance as they are rotated back and forth by the movement 95 of the car 12.

It may be added that the device is adaptable for amusement parks in which case 100 human beings may take the place of the balls 15 to be lowered from the top to the bottom of the shaft 1. It could also be used for lowering débris in wrecking buildings and other similar purposes.

Having now described my invention that 105 which I claim to be new and desire to procure by Letters Patent is:

In combination an upright runway, a carriage sliding in said runway, an inwardly inclined trough projecting partly into the upper end of said runway, a shaft carried at the top of said runway, a pulley 110 on said shaft, an upright handle mounted upon said carriage, a cable secured at one

end of said handle and passing over said pulley, a weight secured to the free end of said cable preponderating over said carriage to normally lift the latter in said runway, a trip lever mounted upon said trough, a part carried by said lever arranged to prevent the sliding of a ball down said inclined trough, said handle arranged to trip said lever to allow a ball to slide into said carriage whereby, said carriage will be im-

pelled downwardly, and a stop on the bottom of said runway with which said carriage is arranged to contact whereby it will be raised.

In testimony whereof I affix my signature 15
in presence of two witnesses.

EDWARD J. CHRIST.
